UNITED STATES PATENT OFFICE.

JOSEPH B. CROSBY, OF FREMONT, OHIO, ASSIGNOR OF ONE-SIXTH TO ALFRED F. GERBER
AND ONE-SIXTH TO CHARLES K. KARLOVETZ, BOTH OF FREMONT, OHIO.

HAT-PIN PROTECTOR.

1,119,245.

Specification of Letters Patent.

Patented Dec. 1, 1914.

Application filed May 3, 1913. Serial No. 765,320.

To all whom it may concern:

Be it known that I, JOSEPH B. CROSBY, a citizen of the United States, residing at Fremont, in the county of Sandusky and 5 State of Ohio, have invented certain new and useful Improvements in Hat-Pin Protectors; and I do hereby declare the following to be a full, clear, and exact description of the invention, such as will enable others 10 skilled in the art to which it appertains to make and use the same.

This invention relates to new and useful improvements in hat pin protectors, and has for its object to provide a device of the 15 above character wherein the clamping action on the point of the hat pin is obtained by means of resilient wire coiled, as will be described hereinafter.

Another object of my invention is to provide a device which will protect the public 20 against injury.

A still further object of my invention is to provide a device of the above character which will be simple in operation, cheap to 25 manufacture, and may be formed of a single piece of material.

With the above and other objects in view, I will now proceed to describe my invention in the following specification and accompanying drawings, in which—

Figure 1 is a side elevation of my improved hat pin protector, as it would appear with the pin in place; Fig. 2 is a detail view of the protector as the same would appear with the pin withdrawn; and Fig. 3 35 is a side view thereof as the same would appear during the process of manufacture.

Referring to the drawings by characters of reference, 1 indicates the shank of a hat 40 pin, to which is attached the usual head portion 2. This shank is extended, as clearly illustrated, and provided with a point opposite the head, which is adapted to enter the hat pin protector indicated generally at 3.

The hat pin protector 3, as clearly illustrated in the drawings, Figs. 1, 2 and 3, has the projecting end 6 of the tubular portion 5 extended, as clearly shown at 9, and bent 50 upwardly, as indicated at 10, and thence rearwardly, as indicated at 11, at which point it enters the opposite end of the tubular member and causes said tubular member to take substantially the same configuration as that illustrated in Fig. 2. In Fig. 3

it will be seen that the end 11 is not inserted in the opening in the tubular member, and this figure has been added to clearly illustrate the action which will be taken when the point 11 is sprung upwardly and 60 into the opening formed in the tubular member. It will be clearly understood upon referring to Fig. 3 that should it be so desired, the end 11 may be removed from the body portion 5 and in this position it will be evident that the body portion will spring into 65 such a position as to form a tube having a straight passage.

It will be clearly seen, upon referring to the drawings, that when the point of a hat pin is inserted in the hat pin protector it will have the tendency to straighten the same, as clearly illustrated in Fig. 1, and thus bind the point firmly into the opening, whereby unintentional removal is substantially 70 eliminated.

While in the foregoing I have shown and described the preferred embodiment of my invention, I wish it to be understood that I may change the specific arrangement of 80 parts as defined by the appended claims without in any way departing from the spirit and scope of my invention.

Having thus fully described my invention, what is claimed is:

1. In a device of the character described, a tubular body portion comprising a coil of wire, one end of said coil of wire being extended and bent to form a hook, said hook being adapted to enter the tubular body portion at the opposite end and cause said body portion to bend to form a tortuous passage therethrough, the walls of which are adapted to engage the shank of a hat pin when the device is in use.

2. In a device of the character described, a tubular body portion, an extension formed at one extremity thereof, and integral therewith, said extension projecting rearwardly to substantially the rearmost extremity of 90 the tubular member, a projection formed integrally with the end of the rearwardly extending member, said projection being bent and adapted to enter the opening in the tubular member to normally hold said tubular member in a bowed position and form a tortuous passage therethrough.

3. In a device of the character described, a tubular body portion comprising a continuous coil of wire, one end of said body 100

portion being extended and bent rearwardly, the rearmost extremity of said extension being bent to form a substantially U-shaped member, one arm of said U-shaped member adapted to enter the opening in the tubular member and cause the tubular member to bend and thereby form a tortuous passage through the center of the tubular member whereby the walls of said passage will fric-

tionally engage the shank of a hat pin when 10 the device is in use.

In testimony whereof I affix my signature in presence of two witnesses.

JOSEPH B. CROSBY.
